UNITED STATES PATENT OFFICE.

JOHN S. SHANKS, OF CANTON, OHIO, ASSIGNOR TO THE CANTON CLOTHES DRYER COMPANY, OF CANTON, OHIO, A CORPORATION OF OHIO.

ELECTRIC CLOTHES DRIER.

Application filed February 6, 1922. Serial No. 534,330.

To all whom it may concern:

Be it known that I, JOHN S. SHANKS, a citizen of the United States, residing at Canton, in the county of Stark and State of Ohio, have invented certain new and useful Improvements in Electric Clothes Driers, of which the following is a specification.

The invention relates to clothes drying cabinets containing electric heaters, and the object of the improvement is to create a constant circulation of a large volume of uniformly heated air throughout the interior of the cabinet.

Electric heaters do not create air currents by direct or induced drafts caused by the combustion or elimination of heated gases, and difficulty has been experienced in uniformly circulating the air in all portions of the electrically heated clothes driers, without the use of ventilating fans.

The present invention involves the use of an elongated drying cabinet having an electric heater located in or near the bottom throughout a considerable portion of its length, guide walls rising from the bottom forming air heating and circulating compartments extending and opening upward from the heating units, and an air vent pipe above the heater extending longitudinally through the air heating compartment drawing air from the lower portion of the cabinet at one end and discharging it outside the cabinet at the other end.

A practical embodiment of the invention is illustrated in the accompanying drawings, forming part hereof, in which—

Figure 1 is a longitudinal elevation section through the middle of the drier cabinet;

Fig. 2, a plan section of the bottom of the same, omitting the electric heater, on lines II—II, Figs. 1 and 4;

Fig. 3, a plan section of same above the vent pipe, showing the electric heater, on lines III—III, Figs. 1 and 4;

Fig. 4, a transverse elevation section near the middle of the drier cabinet, on lines IV—IV, Figs. 1, 2 and 3; and

Fig. 5, a fragmentary detached perspective view of one end of the air heating guiding compartments.

Similar numerals refer to similar parts throughout the drawings.

The drier cabinet may be and preferably is made of sheet metal in the manner set

forth in my copending application for clothes driers, filed December 21, 1921, Serial No. 523,932, with a series of air inlet apertures 6 and 7 in the base and bottom walls 8 and 9, for receiving air into the bottom of the cabinet; the bottom wall apertures 7 being located and distributed as may be desired underneath the electric heater 10 which rests upon the bottom wall of the cabinet, and may consist in one or more units longitudinally located in the median line of the cabinet.

A plurality of air guiding walls rising from the bottom of the cabinet on each side of the heater intermediate the same and the adjacent walls 11 and 11' of the cabinet, and as shown two guide walls 12 and 13 may be provided on each side, having their ends connected and closed by end walls 14, to form an air heating compartment 15 around the heater, and air guiding compartments 16 and 17 on each side thereof, which side compartments may extend around the air heating compartment ends of the heater, as shown at 17' and 17'' for the outer compartment. All the air compartments are open above, so as to freely pass air upward and downward for creating a circulation of the same in the cabinet.

A longitudinal air vent pipe 18, preferably made of sheet metal, extends longitudinally through the air heating compartment 15 above the electric heater, which pipe is preferably inclined upward from one end of the cabinet to the other end and may be provided with a down turned elbow 18' having its lower end opening below from near the bottom of the cabinet in the middle of the end 17' of the outer air guiding compartment. The other end 18'' of the pipe extends through the other end wall of the cabinet, where it may communicate with a vent flue 19 which in turn may communicate with a pipe 20 leading laterally to a chimney or the like, and for preventing the draft of the chimney on any back pressure there may be therein, from affecting the normal operation of the drier, a number of vent holes 20' and 20'' may be arranged in the under side of the pipe 20 and in the chimney collar 20a. The presence of air vents in the outlet pipe also cooperating with the air inlets in the bottom of the drier to equalize air conditions external to the drier.

When the electric heater is in operation,

- air received through the base and bottom inlet apertures 6 and 7 is heated and rises in the heating chamber 15 against and around the air vent pipe, thereby heating the same and causing the air within it to flow toward its upper end and out through the vent and chimney flues, thereby creating a draft for drawing air into the lower end of the vent pipe from the bottom of one end of the cabinet. A secondary bottom wall 21 may be provided in the one end of the heater around the receiving end of the air vent pipe, to form a vent chamber 22 communicating with the receiving end of the pipe. A series of vent apertures 23 are provided in the secondary bottom along each side of the cabinet, through which air is drawn from the guide chambers 17 along the sides of the cabinet.
- 20 A plurality of longitudinal bars 24 supported by brackets 25 at each end of the cabinet, are arranged in convenient manner for carrying various kinds of clothes and the like in the upper part of the cabinet, and a transverse screen 26 is preferably mounted immediately above the air guide walls to prevent the clothes from hanging or dropping upon the air vent pipe and the electric heater. Electric conductors 27 may extend from the heater through the wall of the cabinet, as at 28, and thence to a switch box 29 which may be mounted for convenient access at one end of the cabinet, which is provided in one side with suitable doors as 30, for giving access to the dryer chamber 31.

When the electric heater is in operation the air heated thereby rises upward in the heating chamber 15, and after impinging and passing around the sides of the vent pipe, passes on upward into the drier chamber toward the top thereof. The air displaced by the rising current of heated air flows downward along the side walls of the cabinet, and when it reaches the upward edges of the air guiding walls 12 and 13 the outer portion of the air current passes on downward between the outer guide wall 13, through the guiding chamber 17 formed by the adjacent side wall of the cabinet, and is thence drawn by the suction created by the heated vent pipe 18 to the receiving end thereof, whence this portion of the air is discharged from the cabinet through the vent pipe.

60 The inner portion of the descending air current enters the air guiding chamber 16 between the walls 12 and 13 to the bottom thereof, whence it is drawn through a series of suction apertures 32 provided along the bottom of the guide walls 12, into the bottom of the heating chamber 15; which suction is created by the upward flow of heated air therein.

65 It will be understood that the combined

area of the air receiving apertures 6 and 7, respectively, is such that the volume of air received from outside the cabinet is less than the volume of air which can be heated and caused to flow upward by the electric heater, thereby creating a downward suction in the air guiding chambers 16 on each side of the heating chamber 15, similar to the downward suction created in the outward air guiding chambers 17 by action of the air vent pipe, so that the currents of cooler air descending along each side wall of the heater is divided at the upper edge of the air guiding wall 13, and one portion thereof is discharged from the cabinet through the vent pipe while the other portion thereof is reheated and again circulated through the cabinet with the fresh air received through the bottom apertures.

By these means a constant current of heated air is circulated uniformly through all parts of the cabinet, which may be generally in the form of a current of hotter air rising intermediate the side walls to the top of the chamber and two currents of cooler air descending along the side walls to the bottom of the cabinet, where the cooler currents are divided into two portions, one of which is discharged from the cabinet through the vent pipe and the other of which is reheated and recirculated by the electric heater.

The use of a second guide wall 13 in each side is not essential, but the same is preferred to prevent an interference between the suction through the apertures into the heating chamber and the suction from the air guiding chamber with the air vent pipe.

I claim:

1. A drier for clothes and the like, including a normally closed cabinet with air inlets and a heater in the bottom thereof, means extending over the heater for discharging air from the bottom of the cabinet.

2. A drier for clothes and the like, including a normally closed cabinet with air inlets and an air heating compartment in the bottom thereof, means guiding heated air upward intermediate the sides of the cabinet, means guiding cooler air downward at the sides of the cabinet, and means guiding a portion of the cooler air into the bottom of the air heating compartment.

3. A drier for clothes and the like, including a normally closed cabinet with air inlets and a heater in the middle of the bottom thereof, means guiding heated air upward intermediate the sides of the cabinet, means guiding cooler air downward at each side of the cabinet, means for discharging a portion of the cooler air from the bottom of the cabinet at the middle of one end thereof.

4. A drier for clothes and the like, including a normally closed cabinet with air inlets and an air heating compartment in the bottom thereof, means guiding heated

air upward intermediate the sides of the cabinet, means guiding cooler air downward at the sides of the cabinet, and means guiding a portion of the cooler air into the bottom of the air heating compartment and discharging the remainder thereof from the bottom of the cabinet.

5. A drier for clothes and the like, including a normally closed cabinet with air inlets and a heater in the bottom thereof, walls rising from the bottom of the cabinet forming an air heating compartment around the heater and air guiding compartments on each side thereof with apertures 10 in the bottom of the walls between the air heating and guiding chambers.

6. A drier for clothes and the like, including a normally closed cabinet with air inlets and a heater in the bottom thereof, walls rising from the bottom of the cabinet forming an air heating compartment around the heater and two air guiding compartments on each side thereof with apertures 20 in the bottom of the walls between the heating and inner guiding chambers.

25. 7. A drier for clothes and the like, including a normally closed cabinet with air inlets and a heater in the bottom thereof, walls rising from the bottom of the cabinet

forming an air heating compartment around the heater, and an air vent pipe extending longitudinally through the heating compartment above the heater having one end opening near the bottom of the heater and the other end opening outside the cabinet. 35

8. A drier for clothes and the like, including a normally closed cabinet with air inlets and a heater in the bottom thereof, walls rising from the bottom of the chamber forming an air heating compartment around the heater and air guiding compartments on each side thereof, with apertures at the bottom of the walls between the heating and guiding chambers, and an air vent pipe extending longitudinally through the air 40 heating chamber above the heater having one end opening near the bottom of the heater of the cabinet and the other end opening outside the cabinet.

9. A drier for clothes and the like, including a normally closed cabinet with air inlets and a heater in the bottom thereof, means discharging air from the bottom of the cabinet, and a pipe leading from the air discharging means to a chimney or the like, 50 there being apertures in the pipe for equalizing air conditions external to the drier. 55

JOHN S. SHANKS.
